UNITED STATES PATENT OFFICE.

JOHN H. KLEIN, OF DENVER, COLORADO.

METALLIC-RAIL-TIE FASTENER.

1,257,247.

Specification of Letters Patent. Patented Feb. 19, 1918.

Application filed September 11, 1917. Serial No. 190,846.

To all whom it may concern:

Be it known that I, JOHN H. KLEIN, a citizen of the United States, residing at Denver, in the county of Denver and State 5 of Colorado, have invented new and useful Improvements in Metallic-Rail-Tie Fasteners, of which the following is a specification.

This invention relates to an improvement in rail ties and rail fasteners therefor, and 10 has for its primary object to produce a tie comprising a metallic channeled member having rail engaging elements engaging therewith in such a manner as to permit of the quick arrangement of the said elements 15 upon the tie to engage with the rail or to remove the same from the tie, the said elements, when arranged upon the tie, not only effectively holding the rail to the tie, but serving as reinforcing devices for the tie.

20 Other objects and advantages will appear as the nature of the invention is more fully understood, reference being had to the accompanying drawings, in which,

Figure 1 is a perspective view illustrating 25 the application of the improvement.

Fig. 2 is an approximately central vertical longitudinal sectional view through the same.

Fig. 3 is a transverse sectional view approximately on the line 3—3 of Fig. 2.

Fig. 4 is a fragmentary perspective view looking toward one of the ends of the tie, the rail engaging elements being removed.

Fig. 5 is a perspective view of the insulating members which may be employed, the same being partly separated.

Fig. 6 is a perspective view of one of the rail engaging elements.

Fig. 7 is a similar view of the other rail 40 engaging element.

Fig. 8 is a similar view of the rail plate.

As disclosed by the drawings, each of the ties 1 is in the nature of a cross sectionally U shaped or channel metallic member, the 45 sides 2 of which being parallel and the connecting element or base 3 for the said sides being disposed at a right angle with respect to the sides. By this construction, it will be noted that the channel tie may receive

therein, suitable ballast to hold the tie 50 against lateral, longitudinal or tilting movements.

The sides 2 of each of the ties 1, at a suitable distance from the ends thereof, are provided with substantially U shaped slits and 55 the metal bounded by the said slits is bent inwardly providing the inner faces of said sides with lugs 4 which are arranged in oppositely disposed pairs. Preferably, the lugs are arranged at an angle with respect to 60 the sides of the tie, as clearly illustrated by the drawings, and one pair of lugs is arranged nearer to one of the ends of the tie than is the other pair of lugs. The sides of the tie, at a suitable spaced distance from 65 each pair of lugs are provided with openings 5—5, the oppositely disposed openings being arranged in alinement, as clearly illustrated by the drawings.

The rail engaging members are indicated, 70 for distinction, by the numerals 6 and 7 respectively, the member 6 engaging with one of the sides of each of the rails 8 and the member 7 engaging with the opposite side

75 of the rails. Each of the rail engaging members 6 and 7 includes a flat base portion 9 of a width equal to the distance between the spaced sides 2 of the ties or slightly in excess of such distance. The base, upon the inner end thereof, is provided with a vertically 80

extending flange 10, which is designed to contact with the longitudinal edges of the base flanges of the rails 8, and formed with the upstanding portion or flange 10 is an angularly disposed extension providing a 85

flange 11 that is designed to overlie the flange of the base of the said rails, while formed upon the end of the said flange 11 is a vertically disposed plate 12 which is designed to be received in the fishing spaces of 90

the rails and to underlie the heads of the said rails. In instances, where two rails 8 have their ends abutting at the center of the tie and are to be connected, the plates 12 project a suitable distance from the opposite 95 edges of the angular flange 11 and are provided with openings which register with the bolt openings in the webs of the rails, the or-

dinary connecting bolts passing through the registering openings and the usual securing nuts being provided for the said bolts.

Integrally formed upon the under faces of the base portions 9 of the rail engaging members 6 and 7 are angularly disposed plates 13—13, the said plates being set in from the edges of the said base portions, whereby the said depending plates or flanges 13 will frictionally engage with the inner faces of the said sides, permitting the portions of the base outward of the said plates or flanges to rest directly upon the outer edges of the sides of the tie. The side plates 13 are extended a distance beyond the base approximately equaling the distance between the said base and the plate 12, and the plates 13 of the rail engaging members 6, at the referred to inner ends thereof are formed with angularly disposed hook shaped portions 14, and these hooks are designed to engage with the lugs 4 when the member 6 is disposed over the ties and moved longitudinally of the said ties to permit of the hooks thereof engaging with the lugs. The side plates 13 upon the rail engaging members 7 are provided with openings 15 which are in alinement, and these openings are designed to be arranged in alinement with the openings 5 in the sides 2 of the ties, when the rail engaging members 7 are brought to rail engaging position, and passing through the said alining openings are wedge shaped locking members 16, each having its reduced end provided with an elongated slot 17 through which is passed a wedge key 18 that contacts with the outer surface of one of the sides of each of the ties, and if desired, the reduced end of the said wedge key may be slit, and bent in opposite directions to insure the retention of the key upon the locking members 16. The arrangement of the locking members 16, as above described, will cause the rail engaging elements 7 to be moved toward the rails, it being of course, understood that the said members are inserted in the channels of the ties and moved longitudinally of the said ties to bring the openings in the sides thereof in alinement with the openings in the sides of the ties.

Before the rail engaging members 7 are positioned upon the ties, as just described, I arrange upon the tie, and in contacting engagement with the vertical flange 10 of the rail engaging member 6, a rail plate 19. This plate has its ends provided with downturned flanges 20, the same being designed to frictionally engage with the outer faces of the sides 2 of the ties 1, and upon the plates 19, the rails, of course, rest. By providing the plate 19 with the flanges 20 which engage with the outer sides of the ties 1, and by providing the rail engaging elements with the flanges or sides which engage with

the inner faces of the sides of the tie 1, it will be noted that the said sides of the said ties will be positively retained in proper spaced relation with each other, as the same cannot yield either in an inward or an outward direction, and it will be thus noted, that the rail engaging elements, in connection with the rail plates not only serve as means for supporting and securing the rails upon the tie, but also serve as means for effectively reinforcing and strengthening the tie.

In instances, when the tie and rail securing elements are to be employed upon electric lines, I provide insulating means, illustrated in Fig. 5 of the drawings, which comprises two members, each including a base 21, which, for the major portion of its length, is reduced as at 22, the reduced portion of the base of one of the sections being received by the reduced portion of the base of the other section. Upon the outer edge of the base of each of the members, is formed a vertically extended flange 23 designed to contact with the outer edge of the rails, it being understood, of course, that the base portions of the members 21 rest upon the rail plate and receive the base of the rail. Integrally formed with the vertical extension 23 is an inwardly extending angular flange 24, overlying the base portions of the rail, and upon the inner edges of the said flanges 24 are vertical plates or flanges 25 received in the fishing spaces of the rails, and having their upper edges bent outwardly to overlie the vertical plates upon the inner ends of the rail engaging elements 6 and 7.

It is, of course, to be understood, that, if desired, I may arrange upon the rail plates 19 suitable cushioning means, and from the foregoing description, when taken in connection with the drawings, the construction and advantages of the device, will, it is thought be apparent without further detailed description.

The plate, illustrated in Fig. 8 of the drawings, is preferably in the nature of an insulating material so that the same may be employed when a non-conductor of electricity is necessitated.

Having thus described the invention, what I claim is:

In a device for the purpose set forth, a tie comprising a metallic channel member having oppositely disposed lugs upon the inner sides thereof and having openings disposed adjacent the lugs, rail engaging elements for the tie, each including a base designed to rest upon the tie and having its ends provided with an extension to contact with the edge of a rail and to be received in the fishing spaces of the rails, depending plates upon the base portions of the said elements,

hooks upon the plates of one of the said elements designed to engage the referred to lugs of the tie, the plates of the other element having openings designed to be brought 5 to register with the referred to openings in the sides of the tie, a rail plate between said elements having its ends flanged to engage with the outer sides of the tie, and a wedge member passing through the referred to openings in the sides of the tie and in 10 the plates of the rail engaging element for securing the said element to the tie, and means for securing the said wedge member in locking position.

In testimony whereof I affix my signature. 15
JOHN H. KLEIN.

Copies of this patent may be obtained for five cents each, by addressing the "Commissioner of Patents, Washington, D. C."
